UNITED STATES PATENT OFFICE

121,291

DESIGN FOR AN ELECTRIC LIGHTING FIXTURE

George Ainsworth, New York, N. Y.

Application March 19, 1940, Serial No. 91,061

Term of patent 14 years

To all whom it may concern:

Be it known that I, George Ainsworth, a citizen of the United States, residing at New York, in the county of New York and State of New York, have invented a new, original, and ornamental Design for an Electric Lighting Fixture, of which the following is a specification, reference being had to the accompanying drawing, forming part thereof.

Fig. 1 is a side elevational view of the electric lighting fixture showing my new design.

Fig. 2 is a bottom plan view of the reflector member of the electric lighting fixture shown in Fig. 1 with only a portion of the ornamentation shown complete, it being understood that the unornamented portion involves a mere repetition of the portion shown in solid lines.

What I claim is:

The ornamental design for an electric lighting fixture, substantially as shown and described.

GEORGE AINSWORTH.
